UNITED STATES PATENT OFFICE.

JOHN M. SCOTT, OF RACINE, WISCONSIN, ASSIGNOR TO OTTO R. BARNETT, OF CHICAGO, ILLINOIS.

RAIL-ANCHOR.

1,347,595.

Specification of Letters Patent. Patented July 27, 1920.

Application filed November 8, 1918. Serial No. 261,694.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification.

My invention relates to devices for preventing the longitudinal or creeping movement of railroad rails, these devices being commonly called anticreepers, rail stays or rail anchors; and the primary object of the invention is to provide an anticreeping device which will be light, strong, convenient to attach and remove from the rail, and which can be made to take a firm and permanent hold on the rail. The invention contemplates more particularly a device in which the hold on the rail is accomplished by the wedging action of the parts of the anchor, and one of the important objects of the invention is to provide a simple expedient for locking the wedged elements of the device in engagement with each other so that the grip of the anchor cannot become loosened by vibration or other disturbing forces.

The invention is illustrated, in a preferred embodiment, in the accompanying drawings wherein—

Figure 1 is a fragmentary plan view of a railroad rail and cross tie showing the rail anchor of my invention applied to the rail and bearing against the tie.

Figs. 2, 3 and 4 are sectional views on lines 2—2, 3—3 and 4—4, respectively, of Fig. 1.

Fig. 5 is a sectional view on line 5—5 of Fig. 4.

Fig. 6 is a view, in perspective, of one of the members of the anchor.

Fig. 7 is a similar view of the other or key member of the anchor, and

Fig. 8 is a sectional view, on a somewhat larger scale, taken on line 8—8 of Fig. 1.

Like characters of reference designate like parts in the several figures of the drawings.

Referring to the drawings, 10 indicates the rail having a base flange 11. 12 is one of the ties on which the rail is supported.

The anchor consists, in the preferred embodiment of the invention shown, of two

members, a principal or body member 13 (Fig. 6) and a key member 14 (Fig. 7). 55 The body of the anchor is provided at one end with suitable means for engaging one edge of the base flange of the rail. For example, it may be formed with an integral jaw 15 which fits closely over the base 60 flange. At the other end it is formed with a rib 16 which is preferably tapered in width, being wider at the end remote from the tie against which the anchor is abutted, and narrowing in the direction toward the 65 tie. The center portion of the body member of the anchor consists of a relatively thin web 17 provided at its edges with strengthening ribs 18 and 19, the latter rib being widened to provide a flange or plate 70 20 adapted to bear against the vertical face of tie 12. The end of the body of the anchor which is formed with the rib 16 may be further strengthened by means of a depending web 21. The end of the web 17 adjacent 75 the rib 16 is formed on the under side with a thickened part providing a wedging surface 22 with which the key member 14 cooperates. The key member 14 is formed with a slit or bifurcation 23 so that the key 80 will straddle the web 17 of the body member. The upper part of the key is formed with a lip 24 adapted to overlap the base flange of the rail and with a bendable lug 85 25 which extends over the top of rib 16 and can be bent so as to bear against the outer side of the rib.

In applying the device to a rail the body member is placed on the rail with its tie abutting plate or flange 20 bearing against 90 the face of the cross tie and the bifurcated key 14 is driven upon the web of the body between the edge of the rail base and rib 16. A double wedging action takes place due to the fact that the inner face 26 of the 95 rib 16 has a slight inclination inwardly in the direction toward the tie and because of the provision of the web with the wedging surface 22. In other words, in driving the wedge home it is forced inwardly against 100 the rail and is also driven tightly on the web, the wedging surface 22 tending to force the upper and lower members of the key apart.

When the device has been applied to the 105 rail the projecting lug 25 is bent over, with

a hammer, so that it overlaps the side of the rib 16, as indicated at 25^a in certain of the figures. By tapering the rib 16 as shown a lock is provided which positively 5 prevents any reverse movement of the key.

I claim:

1. A rail anchor comprising a member to extend under the base flange of a rail, and a key adapted to be driven between said 10 member and the rail and provided with a bendable portion on its side adapted to be bent downwardly into locking engagement with the said member to prevent reverse movement of the key.
- 15 2. A rail anchor comprising a member to extend under the base flange of a rail and formed with a rib, and a key adapted to be driven between said member and the rail and provided with a lug vertically bendable over said rib to prevent reverse movement of the key.
- 20 3. A rail anchor comprising a member to extend under the base flange of the rail and formed with a longitudinally tapered 25 rib and a key adapted to be driven between said member and the rail and provided with a lug bendable over a tapered portion of said rib to prevent reverse movement of the key.
- 25 4. A rail anchor comprising a member to extend under the base flange of a rail provided at one end with means for engaging one edge of the base flange of the rail and at the other with an upstanding vertical 30 rib, and a key adapted to grip the base flange of rails of various thickness to be driven between the base flange of the rail and said rib provided with means for engaging said rib whereby reverse movement 35 of the key is prevented.
- 35 5. A rail anchor comprising a member to extend under the base flange of a rail provided at one end with means for engaging one edge of the base flange of the rail and at the other with an upstanding rib, and a key adapted to be driven between the base flange of the rail and said rib formed with a lug bendable over the longitudinal edge 40 of said rib to prevent reverse movement of the key.
- 40 6. A rail anchor comprising a member to extend under the base flange of a rail provided at one end with means for engaging one edge of the base flange of the rail and at the other with an upstanding, longitudinally tapered rib, and a key adapted to be driven between the base flange of the rail and said rib formed with a lug vertically bendable over said rib.
- 45 7. A rail anchor comprising a member to extend under the base flange of a rail provided at one end with means for engaging one edge of the base flange of the rail and at the other with an upstanding rib tapered 50 toward the tie, and a key adapted to be driven between the base flange of the rail and said rib, formed with a lug bendable over said rib to prevent reverse movement of the key.
- 55 8. A rail anchor comprising a member provided at one end with means for engaging one edge of the base flange of a rail and with a web to extend under said base flange and with a rib at the opposite end of the web, and a bifurcated key adapted to be driven astride said web to engage the other edge of the base flange of the rail. 75
- 60 9. A rail anchor comprising a member provided at one end with means for engaging one edge of the base flange of a rail and with a web to extend under said base flange, and a bifurcated key adapted to be driven astride said web to engage the other edge of the base flange of the rail in engagement with a wedging surface on the web which tends to spread the upper and lower parts of the key. 80
- 65 10. A rail anchor comprising a member provided at one end with means for engaging one edge of the base flange of a rail, with a web to extend under said base flange and with a rib at the opposite end of the web, and a bifurcated key adapted to be driven astride said web between said rib and the base flange of the rail. 85
- 70 11. A rail anchor comprising a member provided at one end with means for engaging one edge of the base flange of a rail, with a web to extend under said base flange and with a rib at the opposite end of the web, and a bifurcated key adapted to be driven astride said web between said rib and the base flange of the rail, said key and the aforesaid members of the anchor being formed with wedging surfaces whereby the wedge when driven into place is forced inwardly against the rail base. 90
- 75 12. A rail anchor comprising a member provided at one end with means for engaging one edge of the base flange of a rail, with a web to extend under said base flange and with a rib at the opposite end of the web, and a bifurcated key adapted to be driven astride said web between said rib and the base flange of the rail, said key and the aforesaid members of the anchor being formed with wedging surfaces whereby the wedge when driven into place is forced inwardly against the rail base and is spread over said web. 95
- 80 13. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 100
- 85 14. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 105
- 90 15. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 110
- 95 16. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 115
- 100 17. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 120
- 105 18. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 125
- 110 19. A rail anchor comprising a member provided at one end with means for engaging one edge of the base flange of a rail, with a web to extend under said base flange and with a rib at the opposite end of the web, a bifurcated key adapted to be driven astride said web between said rib and the base flange of the rail, and a lug which is bendable to engage said key with the other member of the anchor. 130

ing one edge of the base flange of a rail, with a web to extend under said base flange and with a rib at the opposite end of the web, and a bifurcated key adapted to be driven 5 astride said web between said rib and the base flange of the rail, said key being formed with a lug adapted to be bent over said rib.

15. A rail anchor comprising a member provided at one end with means for engaging one edge of the base flange of a rail, with a web to extend under said base flange and with a rib at the opposite end of the web, and a bifurcated key adapted to be driven astride said web between said rib and the base flange of the rail, said key being formed with a lug adapted to be bent over said rib, and the rib being tapered in the direction toward the tie.

16. A rail anchor comprising a web to extend under the base flange of a rail, a jaw at one end of the web and a rib upwardly projecting from the other end, and a bifurcated key adapted to be driven astride said web between the rib and base flange of the 25 rail.

17. A rail anchor comprising a web to ex-

tend under the base flange of a rail, a jaw at one end of the web and a rib upwardly projecting from the other end, a bifurcated key adapted to be driven astride said web 30 between the rib and base flange of the rail, and means for preventing reverse movement of the key.

18. A rail anchor comprising a web to extend under the base flange of a rail, a jaw 35 at one end of the web and a rib upwardly projecting from the other end, and a bifurcated key adapted to be driven astride said web between the rib and base flange of the rail, said key being formed with a lug adapt- 40 ed to be bent over said rib.

19. A rail anchor comprising a web to extend under the base flange of a rail, a jaw at one end of the web and a rib upwardly 45 projecting from the other end, and a bifurcated key adapted to be driven astride said web between the rib and base flange of the rail, said key being formed with a lug adapt- ed to be bent over said rib, and the rib being tapered in the direction toward the tie. 50

JOHN M. SCOTT
